CONTAINER

Alexander S. Speer, Buffalo, N. Y.

Application June 8, 1935, Serial No. 25,656

9 Claims. (Cl. 99—180)

This invention relates to a container which is more particularly intended for packaging, enclosing or wrapping a body of ice-cream or similar comestible or like plastic material preparatory to serving this material by the manufacturer or dealer to a customer, a container of this character being shown in U. S. Patent No. 1,612,660 granted December 28, 1926.

One of the objects of this invention is to provide a container of this character which is made of paper or similar sheet-like material in such manner that the same can be produced with a minimum amount of material for each container and completely enclose the body of the material on all sides thereof for protecting the same against contamination by contact with the hands of the party who is manipulating the same.

Another object of this invention is to provide such container with means whereby the same may be readily peeled or removed from the contents which is packed therein, without liability of the hands of the party serving the ice-cream or the like coming in contact therewith.

A further object of this invention is to so construct the container that when the same is opened it presents a plurality of sections which can be readily filled with the material which is to be packed, and thereafter the sections of the container may be closed relative to each other for putting the container in the form in which the parts of the material within the container sections are brought into engagement with each other and the container completely encloses the material to be packed.

Additional objects of this invention are to so construct the container that a plurality of the same may be formed in a longitudinal row from a strip of paper or like sheet material, and the several containers of a row may, while in an open position, be simultaneously filled with the material which is to be packed, and after the filling material has been placed into the plurality of containers, the latter may be closed for completing the formation of a longitudinal row of individual servings of ice-cream or the like, the containers of which are connected with each other and permit of breaking one filled container from another when the same are to be served to a customer.

In the accompanying drawings:

Figure 1 is a fragmentary perspective view of a sheet of material, such as paper, from which a plurality of containers embodying my invention are adapted to be formed.

Figure 2 is a top plan view, partly broken away,

showing a strip of sheet material, such as paper, cut into the required form preparatory to bending or folding the same into a shape which produces a longitudinal row of such containers which are open and in a position to receive the ice-cream filling which is to be packed therein.

Figure 3 is a perspective view, partly broken away, showing a plurality of containers which have been formed by bending or folding the cut strip shown in Fig. 2, so that these containers are arranged in a longitudinal row and are connected with each other and are in an open position ready to receive the filling material which is to be packed therein.

Figure 4 is a top plan view, partly broken away, of a plurality of containers shown in Fig. 3.

Figure 5 is a cross section taken on line 5—5 Fig. 4, showing the companion sections or pair of halves of a container in an open position and filled with sections of the filling material which is to be packed therein and enclosed by the container.

Figure 6 is a similar view showing the two sections of the container folded or closed for bringing the two sections of filling material within the container into engagement with each other so that the same form one body of filling material and also complete the enclosure of this body.

Figure 7 is a longitudinal section, taken on the correspondingly numbered line in Fig. 6, and showing a multiplicity of such completed containers and fillings therein, arranged end to end to form a longitudinal row and showing the opposing ends of adjacent containers connected with each other.

Figure 8 is a fragmentary perspective view of a plurality of filled containers shown in Fig. 7.

Figure 9 is a fragmentary plan view of a cut blank for making a container which is hexagonal in cross section.

Figure 10 is a fragmentary perspective view, showing a plurality of containers bent into semi-complete form from the blank shown in Fig. 9 preparatory to filling the same with material.

Figure 11 is a cross section of a filled and completed container made from the blank shown in Fig. 9.

Figure 12 is a longitudinal section taken on line 12—12 Fig. 11.

Figure 13 is a fragmentary perspective view of a plurality of filled containers shown in Fig. 12.

Figure 14 is a fragmentary plan view of a cut blank for making a container which is square in cross section.

Figure 15 is a fragmentary perspective view

showing a plurality of containers bent into semi-complete form from the blank shown in Fig. 14, preparatory to being filled with material.

Figure 16 is a cross section of a filled and completed container made from the blank shown in Fig. 14.

Figure 17 is a longitudinal section taken on line 17—17 Fig. 16.

Figure 18 is a fragmentary perspective view 10 of a plurality of filled containers shown in Fig. 17.

In the following description similar characters of reference indicate like parts in the several figures of the drawings:

Referring to Figs. 1-8, the numeral 10 represents a strip of sheet material which preferably consists of a suitable thickness of paper which can be cut and bent or folded into the required shape for producing one container embodying this invention or a plurality of them which are arranged in a longitudinal row.

In the following description this sheet material may for convenience, be referred to as a strip or sheet of paper, but it is to be understood that such use of this term is merely a matter of convenience, and that this invention is intended to include the use of any kind of sheet material which is satisfactory for the making of these containers and packaging or enclosing ice-cream or other comestible or like material which at times is of a plastic character.

The first operation in the production of a plurality of containers from the strip of material shown in Fig. 1 is to cut the same by the use of a suitable press so as to form a plurality of 35 transverse bands 11, 11 which are arranged in a longitudinal row and spaced from each other, and a plurality of pairs of substantially semi-circular head sections 12 arranged adjacent to the transverse edges of each transverse band. Each of the 40 transverse bands 11 comprises two side wall sections 13, 13 which are arranged side by side and are adapted to be folded relatively to each other along a longitudinal line 14 between the same, and at its opposite ends each of the bands 11 is provided with an extension 15 which is adapted to be folded along a longitudinal line 16 between the same and the adjacent outer edge portion of the respective wall sections 13 and to be folded laterally outward on this line, so as to form a longitudinal tab on the respective part of the wall which is adapted to be grasped by the fingers for peeling the container from the filling enclosed thereby in serving this filling to a customer.

The semi-circular head sections 12 adjacent 55 to each transverse edge of one of the wall bands are arranged transversely side by side and the central part of the periphery of each semi-circular head section which ultimately becomes the outer edge portion thereof is connected with the central transverse edge portion of one of the wall sections 13 and is adapted to be folded relative thereto along a transverse line 17 when bending the cut paper blank for producing the respective container.

60 The straight diametrical edge of each semi-cylindrical head section, which ultimately becomes the inner edge of the same, is arranged transversely and parallel with the adjacent transverse edge of the respective wall band.

65 In the case of the endmost pairs of semi-cylindrical head sections of the blank, each of these sections is provided on the side opposite the diametrical edge thereof with a tab or flange 181 which is ultimately used as part of a handle for manipulating or lifting the container blank dur-

ing the operations of placing the container in a mold and also removing the same therefrom, also handling the containers while dispensing their contents. These tabs also serve as means for more effectively closing or sealing the outer diametrical joints of the endmost containers of a longitudinal row so as to guard against contamination.

The diametrical lines of division between the tabs or flanges 181 and their companion head sections 12, as indicated by dotted lines 18 in Fig. 2, 10 are preferably creased, scored, perforated or otherwise weakened so that each of these tabs may be readily bent on the respective line into a position in which it projects laterally relatively to the companion head section, as shown in Figs. 15 3, 4, 7 and 8.

In the case of the pair of semi-cylindrical head sections at the extremities of the strip of paper from which a plurality of containers are made, the diametrical edges of these head sections 20 form the extremities of the latter. In the case, however, of the semi-cylindrical head sections which are arranged intermediate of adjacent wall bands, each semi-circular head section of one wall band is connected with the corresponding 25 semi-cylindrical head section of the adjacent wall band along a transverse diametrical line 19, so that these two head sections in effect produce a complete head which is of circular form. Ultimately the two semi-cylindrical head sections on 30 the corresponding parts of two adjacent wall bands are adapted to be folded relatively to each other along the transverse diametrical line between the same, which line is preferably weakened by perforating, scoring or creasing, as shown in 35 Fig. 2, in order to permit of subsequently readily tearing one of the intermediate head sections on one wall band from the corresponding semi-circular head section 12 of the adjacent wall band for a purpose which will presently appear.

40 After the blank has been cut and prepared in the manner indicated in Fig. 2 the same is bent, folded or formed by any suitable means so as to produce a plurality of pre-formed containers, the parts of which are open and in a position to permit of introducing therein the material which is to be packed or wrapped preparatory to closing the several containers and completing the enclosure or wrapping of the filling within.

45 In order to accomplish this bending or folding of the cut or prepared blank economically and expeditiously, this is preferably accomplished by a suitable machine provided for this purpose.

50 After the prepared blank has been thus subjected to this bending and folding operation, each of the wall sections 13, 13 is converted into a semi-cylindrical shape, the axis of which is arranged lengthwise, and the two semi-cylindrical sections being arranged transversely side by side and connected at their adjacent inner longitudinal edges along the longitudinal line 14 between the same, while the side tabs or flanges 15 at the outer edges of the respective wall sections are bent transversely outward, as best shown in Figs. 3 and 4.

55 The semi-circular head sections 12 on opposite transverse edges of each wall band are also bent inwardly along the lines 17 therebetween into the form of a two ply pleat or loop so that each of these head sections projects from the central part of each semi-cylindrical wall section toward the axis of the same and at right angles thereto, and thus forms a head section for the respective semi-cylindrical wall section at one end thereof, as shown in Figs. 3, 4 and 7. The end tabs 181 are 60 65 70 75 75

also bent longitudinally outward, as shown in Figs. 3 and 4. During this bending of the several head sections, those at the extremities of the blank are merely bent inwardly relative to the axis 5 of the respective wall sections with which they are connected, without affecting any other part of the blank, but the corresponding head sections arranged intermediate of the several wall bands are not only bent inwardly relatively to each other 10 along the weakened line 19, but also folded together so that the plies of the pleat or loop formed thereby are arranged parallel or nearly so, and the adjacent wall bands, of which they form a part, are moved lengthwise toward each other, 15 as shown in Figs. 3, 4 and 7.

When the parts of the pre-formed multiple containers have been thus formed, shaped or positioned a plurality of pairs of semi-cylindrical cells are produced which are arranged in a longitudinal 20 row and the members of each cell are arranged transversely side by side, and each cell has a semi-cylindrical wall section which is connected at its inner edge with the corresponding edge of the companion wall section, while its outer longitudinal 25 edge is provided with a laterally projecting tab or flange 15, and semi-circular heads are arranged at the opposite transverse end edges of the respective wall section and thereby form with the latter one-half of the enclosure of a complete 30 container.

Obviously a single container can be constructed in accordance with the procedure just described, but in practice the forming of a plurality of containers from a single blank in the manner described 35 permits of the economical manufacture of these containers and the subsequent filling of the same with the material which is to be packed.

After a plurality of containers have been thus pre-formed and while the parts are in the relative 40 position shown in Figs. 3 and 4, the material which is to be packed is introduced into the two semi-circular cells of each of the containers so that each section 20 of this filling is of substantially semi-cylindrical form and has its rounded 45 peripheral underside engaging with the inner side of the respective cell wall, while the flat upper side thereof is flush or nearly flush with the upper edges of this cell. The filling of the material to be packed into the cells of the several 50 containers is preferably effected while the cells of each pair are arranged horizontally side by side, and the inner or concave sides of these cells face upwardly, as shown in Fig. 5.

While the material is thus deposited in each cell 55 of a container this material is confined therein by the semi-cylindrical side wall and the semi-circular head sections at opposite ends of this wall.

After the filling material has been thus introduced into the plurality of pairs of cells of the 60 several preformed containers while the latter are in an open position the two like halves of the filled multiple containers are closed or turned transversely relatively to each other so that the flat diametrical sides of the filler sections in the 65 respective cells of the containers engage with each other and thereby complete into cylindrical form a filling in the cooperating halves or sections of each of the containers, as shown in Figs. 6 and 7. When the two halves of each container are 70 thus closed relatively to each other, the corresponding outer longitudinal edges of the two wall sections 13, 13 engage with each other, as shown in Fig. 6, so as to form an enclosure which completely surrounds the perimeter of the contents or 75 filling of the container, and the diametrical free

edges of the head sections on the corresponding ends of the wall sections are brought opposite each other and engage or nearly engage their tabs 181 with one another, as shown in Figs. 7 and 8, whereby the two head sections at each end of 5 a container together practically form a complete circular head which forms a closure for the respective end of the container in the closed position of its parts and effectively protects the ice cream or other contents of the container against 10 contact by hands and thus avoids possible contamination of the same.

In the closed position of the two sections of a container the tabs 15 at opposite ends of its peripheral wall engage with each other, as shown in 15 Figs. 6 and 8, and thereby aiding in sealing the longitudinal joint in the container, similar to the manner in which this is done in Letters Patent No. 1,612,660 hereinbefore mentioned.

When the two sections of each container are closed for completing the encasement of the two semi-cylindrical sections of ice cream or other material therebetween, a small quantity of this material tends to ooze outwardly into the joint split or slit between the fold at the inner edge of each connected pair of head sections 12 on each side of the axis of the containers and the fold at the inner end of the opposite connected pair of head sections, and also into the joint split or slit between the end tabs 181 at each end of a row of containers, also into the joint split or slit between the tabs 15 at the opposite longitudinal edges of each circular wall band, whereby this ooze operates as an adhesive or cementing agent which connects the respective parts of each container and seals these joints so as to protect the contents of the containers against contamination or deterioration.

After the two halves of the multiple container have been thus closed for completing the formation of the containers and enclosing the contents thereof, a plurality of filled containers are produced which are arranged end to end in a longitudinal row. In the case of ice-cream the filled 40 containers are preferably subjected to a further cooling treatment by placing the same in a refrigerator in order to harden and season the ice-cream and cause it to retain its shape preparatory to being served.

During hardening of the ice-cream the opposing relatively flat diametrical surfaces of each unit will adhere to each other and cause the companion sections of ice-cream in each container to practically form a solid integral unit which operates to hold the container in its closed position, so that it is difficult if not impossible to again open the container and separate the ice-cream sections therein.

While the container sections and the filling sections therein are in a closed position the longitudinal hinge or folding line 14 between the two wall sections of each container is arranged in a plane at right angles to the folding lines or hinges 17 between the curved edges of the head sections and the transverse edges of the wall sections 65 whereby the bending lines of each container are distributed over different parts of the blank and a strong and durable container is produced which consists of but a single ply of paper or sheet material throughout the entire container where the 70 same is engaged by the filling or contents, and thus enables the contents of the container to be maintained in a uniform condition and consistency when exposed to different temperatures.

Insertion of the blanks into the molds for hold- 75

ing the same in place, removal of the same after being filled and transferring thereof to a refrigerator as well as subsequent manipulation for dispensing purposes is facilitated by grasping the 5 tabs 181 which may be utilized as handles in addition to serving as means for more effectively sealing the outer ends of the endmost containers of a longitudinal row.

The size of each container is preferably so determined that the contents or filling thereof is suitable for one service to a customer, which quantity is usually referred to as a "portion", "serving" or "unit".

When it is desired to serve a customer with a 15 portion of ice-cream, one of the containers is separated from the others in the longitudinal row of which it is a member by severing the respective container between that end thereof which is connected with an adjacent container. This can be 20 readily accomplished by breaking or severing the two semi-circular head sections 12 of one container from those of an adjacent container along the lines 19, 19 between the corresponding head sections. Owing to these lines being weakened by 25 reason of the formation of perforations, slits, indentations, scores or creases therein, the same permits of readily breaking or tearing off one filled container from another without the use of a knife or other instrument for this purpose.

30 After a filled container has been thus broken off or separated from others of like character the contents of this filled container can be readily deposited upon a dish by grasping with the fingers the two tabs 15 at opposite ends of the peripheral 35 wall of the container and then pulling these two tabs apart, whereby the wall and end heads of the container will be peeled off from the filling of ice-cream or the like and enable the latter to be deposited upon a dish without the fingers of 40 the party serving the same coming in contact with the contents.

This container therefore not only forms a complete enclosure for the contents so as to provide the maximum protection against contamination, 45 but the same also can be easily and conveniently served without coming in contact with the human hands.

Owing to the simplicity of the construction of this container and the advantageous utilization 50 of paper or other material for covering the entire surface of the body or filling of material which is to be packed, edible goods of this character may be protected at a minimum of cost and the goods may also be served very economically, expeditiously and in the best condition.

Instead of making the side wall or body of the containers of cylindrical form in cross section and the heads thereof in the form of round disks, the blank may be cut, as shown in Fig. 9, and bent 60 as shown in Figs. 10-13, so that each of the side walls 131 is of hexagonal form in cross section, and each of the end heads 121 has the form of a hexagonal disk, but in other respects the blank and container are of substantially the same construction as the blank adapted for making a container of cylindrical form in accordance with this invention, which is shown in Figs. 2-8, and corresponding parts therefore are indicated by like reference characters.

70 Similarly the blank may be cut, as shown in Fig. 14, and bent as shown in Figs. 15, 16, 17 and 18, that each of the side walls 122 of the container is of square form in cross section, and each of the end heads 123 has the form of a square 75 disk, but is likewise in other respects substantially

identical with the structure of the blanks and resulting containers shown in Figs. 2-13, and the same description and reference characters are therefore employed to identify corresponding parts of these various forms of the invention.

5 In all of the several forms of this invention a part of each half of the side wall of the container is bent inwardly to form one-half of a complete head for an end of the container, and the body of the container has a longitudinal slit extending throughout the length thereof, so that the container may be readily filled while in an open position and the contents completely covered and protected when the container is closed, and the contents may also be readily discharged without touching the same.

10 I claim as my invention:

1. A container for packaging a filling of plastic material comprising a longitudinal wall adapted to enclose the longitudinal side of the filling and provided with a longitudinal split, and transverse heads adapted to enclose the transverse ends of the filling and each head having a part of its edge connected with a part of the adjacent end of the longitudinal wall and said wall being provided diametrically opposite said split with a longitudinal bendable portion which constitutes a line whereby this wall is divided into two sections each of which is adapted to receive a part of the filling material to be packed and about which line said sections are adapted to be bent for bringing their inner sides opposite to each other and engaging the parts of said material on the inner side of said wall sections with each other.

20 35 40 45 50 55 60 65 70 75 80 85 90 95 100

2. A container for packaging a filling of plastic material comprising a longitudinal wall adapted to enclose the longitudinal side of the filling and provided with a longitudinal split, and transverse heads adapted to enclose the transverse ends of the filling and each head being composed of two sections which have their inner edges opposed and their outer edges connected with diametrically opposite edge portions of the respective end of said wall and said wall being provided diametrically opposite said split with a longitudinal bendable portion which constitutes a line whereby this wall is divided into two sections each of which is adapted to receive a part of the filling material to be packed and about which line said sections are adapted to be bent for bringing their inner sides opposite to each other and engaging the parts of said material on the inner side of said wall sections with each other.

3. A container for packaging a filling of plastic material comprising a longitudinal wall adapted to enclose the longitudinal side of the filling and provided with a longitudinal split, and transverse heads adapted to enclose the transverse ends of the filling and each head being composed of two sections which have their inner edges opposed and their outer edges connected with diametrically opposite edge portions of the respective end of said wall, and the points of connection between the outer edges of the section of each head and the respective end of the side wall being on a plane at right angles to the plane of the longitudinal split in said wall and said wall being provided diametrically opposite said split with a longitudinal bendable portion which constitutes a line whereby this wall is divided into two sections each of which is adapted to receive a part of the filling material to be packed and about which line said sections are adapted to be bent for bringing their inner sides opposite to each

other and engaging the parts of said material on the inner side of said wall sections with each other.

4. A container for packaging a filling of plastic material having the form of a cylinder provided with flat ends, said container comprising a cylindrical wall adapted to enclose the longitudinal side of the filling and provided with a longitudinal split, and flat heads of disk shape adapted to 10 enclose the transverse ends of the filling and each having an edge portion connected with a part of the adjacent end of said wall and said wall being provided diametrically opposite said split with a longitudinal bendable portion which 15 constitutes a line whereby this wall is divided into two sections each of which is adapted to receive a part of the filling material to be packed and about which line said sections are adapted to be bent for bringing their inner sides opposite to each other and engaging the parts of said material on the inner side of said wall sections with each other.

5. A container for packaging a filling of plastic material having the form of a cylinder provided 20 with flat ends, said container comprising a cylindrical wall adapted to enclose the longitudinal side of the filling and provided with a longitudinal split, and flat heads of disk shape adapted to enclose the transverse ends of the filling and 25 each being composed of two semi-circular sections which have their inner straight edges opposed and their outer curved edges connected partly with diametrically opposite edge portions of the adjacent end of said wall and said wall 30 being provided diametrically opposite said split with a longitudinal bendable portion which constitutes a line whereby this wall is divided into two sections each of which is adapted to receive a part of the filling material to be packed and 35 about which line said sections are adapted to be bent for bringing their inner sides opposite to each other and engaging the parts of said material on the inner side of said wall sections with each other.

45 6. A plurality of containers for packaging a plurality of fillings of plastic material arranged in a longitudinal row, each of said containers having a longitudinal side wall enclosing the side of one of said fillings and a longitudinal split in 50 one part thereof, and transverse end heads enclosing the opposite ends of the respective filling and each head composed of two sections which have their inner edges opposed and their outer edges connected with diametrically opposite edge 55 portions of the adjacent end of the respective wall, and the corresponding head sections of adjacent containers having their inner edges connected with each other and said wall being provided diametrically opposite said slit with a longitudinal bendable portion which constitutes a line

whereby this wall is divided into two sections each of which is adapted to receive a part of the filling material to be packed and about which line said sections are adapted to be bent for bringing their inner sides opposite to each other and engaging the parts of said material on the inner side of said wall sections with each other.

7. A container for packaging a filling of plastic material comprising a side wall adapted to surround the perimeter of the filling and having a longitudinal split throughout the length thereof, and a pair of half-heads projecting inwardly from diametrically opposite parts of each transverse edge of the side wall and having their inner ends opposing each other and forming a complete head for the respective end of the container and said wall being provided diametrically opposite said split with a longitudinal bendable portion which constitutes a line whereby this wall is divided into two sections each of which is adapted to receive a part of the filling material to be packed and about which line said sections are adapted to be bent for bringing their inner sides opposite to each other and engaging the parts of said material on the inner side of said wall 20 sections with each other.

8. A new article of manufacture comprising a filling of plastic material, and a container of sheet-like material having a side wall surrounding the perimeter of the filling and provided with a longitudinal split extending throughout the length thereof, and provided at its opposite transverse ends with inwardly bent head portions extending across opposite transverse ends of said side wall and said wall being provided diametrically opposite said split with a longitudinal bendable portion which constitutes a line whereby this wall is divided into two sections each of which receives a part of said filling and about which said wall has been bent for bringing said filling sections into engagement with each other.

9. A new article of manufacture comprising a filling of plastic material, and a container of sheet-like material having a side wall surrounding the perimeter of the filling and provided with a longitudinal split extending throughout the length thereof, and provided on diametrically opposite sides of each end of the side wall with inwardly projecting half-heads which oppose each other and form a complete head for the respective end of the side wall and said wall being provided diametrically opposite said split with a longitudinal bendable portion which constitutes a line whereby this wall is divided into two sections each of which receives a part of said filling and about which said wall has been bent for bringing said filling sections into engagement with each other.

ALEXANDER S. SPEER.
